Primary Examiner — Andrew T Nemeth

CLAIM

The ornamental design for a pet feeder, as shown and described.

DESCRIPTION

FIG. 1 is a front perspective view of a pet feeder, showing my new design;
FIG. 2 is a rear perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof;
FIG. 8 is a bottom view thereof;
FIG. 9 is an enlarged detail view of area 9 in FIG. 2;
FIG. 10 is an enlarged detail view of area 10 in FIG. 3;
FIG. 11 is an enlarged detail view of area 11 in FIG. 3; and,
FIG. 12 is an enlarged detail view of area 12 in FIG. 3.
The dash-dash broken lines in the drawings illustrate portions of the pet feeder, which form no part of the claimed

The dot-dot-dash broken lines in FIGS. 2, 3, and 9-12, illustrate the location and bounds of the enlarged detail views of FIGS. 9-12 and form no part of the claimed design.

1 Claim 12 Drawing Sheets
